Primary Examiner — Paula Greene(74) *Attorney, Agent, or Firm* — LaRiviere, Grubman & Payne, LLP(57) **CLAIM**

The ornamental design for an audio listening system, as shown and described.

DESCRIPTION

FIG. 1 is a perspective view of an audio listening system, showing our design;

FIG. 2 is a front view thereof, shown separately for purposes of illustration;

FIG. 3 is a rear view thereof, shown separately for purposes of illustration;

FIG. 4 is a side view thereof;

FIG. 5 is an opposing side view thereof;

FIG. 6 is a top view thereof; and,

FIG. 7 is a bottom view thereof.

The broken lines showing the environment are for illustrative purposes only and form no part of the claimed design.
